LIPSTICK DISPLAY CASE

John H. Walsh, Boston, Mass.

Application February 18, 1947, Serial No. 137,001

Term of patent 3½ years

(Cl. D80—11)

To all whom it may concern:

Be it known that I, John H. Walsh, a citizen of the United States, residing at Boston, county of Suffolk, and Commonwealth of Massachusetts, have invented a new, original, and ornamental Design for a Lipstick Display Case, of which the following is a specification, reference being had to the accompanying drawing, forming a part thereof.

Fig. 1 is a front perspective view of a lipstick display case, showing my new design.

Fig. 2 is a side view with the cover closed.

I claim:

The ornamental design for a lipstick display case, substantially as shown.

JOHN H. WALSH.
